UNITED STATES PATENT OFFICE.

NELS H. NELSON, OF DES MOINES, IOWA.

AWNING.

Application filed February 23, 1926. Serial No. 89,955.

The object of my invention is to provide an awning of simple, durable and inexpensive construction.

More particularly, it is my purpose to provide a roller mounted flexible awning having novel means for controlling the awning and holding it in different positions of adjustment, whereby it may be variably positioned for shade and storm protection or may be used for covering and protecting a screen, or window and glass, and for controlling ventilation.

Such an awning can be used for window shades, or for porches or the like.

In this connection, it is my object to provide with the roller mounted awning, a means including members hingeable to the window frame or other rigid support to swing substantially in a half circle, by large strong hinges having projecting guide portions for holding the members properly against lateral swinging, and to provide a frame secured to the free edge of the awning, and telescopically connected with said hinged members to afford a strong reinforced frame for supporting the awning in all of its extended positions.

With these and other objects in view, my invention consists in the construction, arrangement and combination of the various parts of my awning, whereby the objects contemplated are attained, as hereinafter more fully set forth, pointed out in my claims, and illustrated in the accompanying drawings, in which:

Figure 1 is a front elevation of an awning embodying my invention installed on a window frame.

Figure 2 is an end elevation of the same.

Figure 3 is an enlarged side elevation, parts being shown in section and parts being broken away.

Figure 4 is a perspective view of a portion of the device, parts being broken away and parts being shown in section.

Figure 5 is a detail, sectional view taken on the line 5—5 of Figure 3.

Figure 6 is an enlarged, detail, sectional view taken on the line 6—6 of Figure 4; and

Figure 7 is a detail, sectional view taken on the line 7—7 of Figure 1.

In the accompanying drawings, I have used the reference numeral 10 to indicate generally

the casing for my improved awning. The casing 10 is quadrangular in cross section, as shown in Figure 4.

Mounted on the ends of the casing are caps 11 which are fastened to the frame 12 of a window or the like.

Received within the casing 10 is a tubular roller 13 on which is wound the awning 14. Received within the roller 13 is a shaft 15, having its ends fixed in the partitions 15^a in the ends of the casing 10 by keys 15^b. A coil spring 16 is mounted on the shaft 15 in the roller 13 and is connected to both of them in such manner as to tend to normally rotate the roller to position where the awning is wound up on the roller within the casing 10.

In the bottom of the casing 10 is a slot 17.

The free edge of the awning 14, which is of canvas or any suitable material is fastened to a binder member, comprising a tubular, cylindrical member 18, having a longitudinal slot, and having its edges adjacent the slot 75 extended to form the parallel strips 19 and 20. The edge of the awning 14 is gripped between the strips 19 and 20, which are spot-welded together, as at 21, through the awning material.

The free edge portion of the awning material is extended from the strips 19 upwardly parallel with the main body of the awning 14, as shown in Figure 6, and is then folded downwardly to overlap the outer face of the strip 20, as at 21. The free edge, which I have indicated generally by the reference character 22, and the folded over portion 21, and the main portion 14 of the awning are fastened together above the strips 19 and 20 by rows of stitches 23 and 24. This covers the outer face of the strip 20 with the canvas or other awning material, and also helps to close the slot 17 when the awning is up.

I provide a U-shaped yoke made of a rod 95 preferably bent and having its central member 25 received in the tubular member 18. (See Figures 4 and 6.)

The ends or arms 26 of the U-shaped yoke are connected with the sides of the frame 12 in the following manner:

Secured to each side of the frame substantially below the casing 10 is a bracket hinge A. Each bracket hinge may comprise a central, deep channel 30 having the side walls 105 29 bent back over on themselves as at 28 to

make a stronger structure, and terminating in flanges 27 forming feet, which are fastened to the rigid support, such as the frame 12.

Pivoted between the walls of each bracket 5 A on each side of the frame by means of a pivot pin 32 is a tubular member 31 open at both ends.

The arms 26 of the U-shaped members hereinbefore referred to are slidably received in 10 the tubular members 31. A portion of the member 18 and of the strips 19 and 20 are cut away to leave a slot, as at 33, to receive a draft means such as a chain 34, extending around and fixed to the rod member 25.

15 On the window sill 36 is a suitable projecting bracket 37 having a roller 38 mounted therein. The chain 34 is extended under the roller 38. The bracket 37 may be provided with a notch or any suitable means may be 20 afforded for fastening the chain in different positions.

It will be understood that normally the spring 16 will hold the awning wound on the roller 13 with the strips 19 projecting into 25 the casing 10.

The tubular member 18 is of such size compared to the width of the slot 17 that it will not pass through the slot.

The bracket 37 projects far enough from the 30 window frame, so that when the awning is wound up, the chain 34 is outside the line X indicated by dotted lines in Figure 2, between the member 25 and the pivot pin 32.

It will thus be seen that when the chain is 35 pulled downwardly or pulled around the roller 38, it will tend to swing the rod portion 25 of the upper part of the U-shaped member downwardly and outwardly.

The arms 26 slide in the tubes 31, as the 40 portion 25 travels in the curved path indicated by the dotted lines 39 in Figure 2. This, of course, pulls out the awning, which may be stopped and held in any position of its travel.

The awning is shown in full lines in its 45 pulled down position in Figure 2.

The spring always tends to pull the awning up and by fastening the chain in any suitable way, the awning can be held in any of its outer positions, and will be inclined away 50 from the window.

The lower, outer end of the awning will be held away from the window in any selected position by the tubes 31.

It will be seen that in the manipulating of 55 the awning, the arms 26 project into the tubes as far as they will go, except when the awning approaches its upper limit of movement, as it is being wound into the casing 10.

The free ends of the arms 26 are limited in 60 their movement into the tubes by the pivot pins 32. The lower end of the awning therefore swings in an arc of a circle having its center in the line of the axes of the pins 32, except only that when the tubes 31 swing upwardly until they are aligned with the slot 17,

the arms 26 slide out partly of the tubes until the tubular portion 18 is in the mouth of the slot 17.

The parts are so arranged that the arms 25 can never slide out of the tubes 31.

In the manner of spot-welding the strips 19 and 20 together with the edge of the awning between them, there is afforded a simple and speedy method of connecting the binding strip to the awning.

By folding over the portions 22, 21 and 14 in the manner shown, the metal strip is covered and another important beneficial result is attained. When the awning is down, as shown in Figure 2, the portion folded over 80 the metal strip sheds water and prevents water from getting into the part of the awning that is gripped between the strips 20 and 19 and causing it to rot.

This structure helps to keep water from between the strips 19 and 20 and avoids corroding them, and protects the interior of the cylindrical member 18 and the member 25 against water and rust and corrosion, which might otherwise interfere with the smooth 90 operation of the device.

It will thus be seen that I have provided a very simple and inexpensive and efficient mechanism for holding the lower end of the awning spaced from the window frame when 95 the awning is pulled out.

I eliminate the necessity for using fixed tracks or guides and provide a frame with telescoping arms, which reinforce each other, so as to get the full strength of both telescoping members during all manipulation of the parts when the awning is partially or wholly drawn out.

The awning can be readily adjusted in any 105 partially extended position, or can be drawn into the plane of the line X to protect the screen, or to protect the glass against rain or hail or to afford shelter and ventilation, even if windows are open, in case of storm, or whenever desired.

The mounting of the member 25 in the tubular portion of the binder strip affords reinforcement for the U frame. This is especially important with wide awnings, because it protects the member 25 against the tendency 115 to bend due to the fact that the pull of the chain 34 is on the center of the member 25.

This also affords a connection between the U frame and the awning, which will not tear or pull or injure the fabric.

I have also provided a simple and effective means for connecting the awning with the binder strip and the yoke, which holds the lower end away from the window frame.

The casing and roller in themselves could be made in any suitable form for cooperation with the rest of the structure.

On the frame 12 are resilient bumpers 40, which take the impact of the member 31, if the chain is released and the spring allowed 130

to draw up the awning and the frame at its lower end so rapidly that the momentum swings the members 31 against the frame 12. The awning remains taut at all times when 5 open, because the spring pulls in one direction and the chain in the other direction.

It is my purpose to cover by my claims, any modified forms of structure or use of mechanical equivalents, which may be reasonably included within their scope, and within the scope of my invention.

I claim as my invention:

1. In a device of the class described, a flexible awning, a binder strip for the free edge 15 of said awning, means for connecting said edge of the awning to said binder strip, said awning being folded over at its free end to cover one face of the binder strip for protecting said means.
- 20 2. In a device of the class described, a flexible awning, a binder strip for the free edge of said awning, said awning being folded over at its free end to cover one face of the binder strip, and a second binder strip spot-welded 25 to the first binder strip with the free edge of the awning between the strips, the free, folded over end of said awning serving to protect spot welded connections.
3. In a device of the class described, a flexible awning, spaced members each pivotally supported at one end, arms extending from the free end of the awning and telescopically connected with said members, and means for pivotally supporting said members comprising 35 hinges formed with parallel side walls projecting out a considerable distance from the pivots and receiving said members between them and adapted to brace the members against lateral swinging movement.
- 40 4. In a device of the class described, an awning roller support, a spring-actuated roller rotatably supported thereon, a flexible awning wound on said roller, a frame comprising a transverse central element rotatably connected with the free edge of the awning, parallel, freely telescoping side frame members extending at right angles to the central element and pivotally mounted at their ends farthest from the awning, a draft element 45 connected to the transverse element of said frame for drawing it toward the pivotal connections and causing a telescoping movement of said side frame members against the action of the spring of said roller and also for causing 50 said side members to swing on their piv-

ots, said draft means and spring cooperating to keep said awning in taut condition.

5. A structure of the class described comprising a spring actuated rolled awning, a frame therefor comprising freely telescoping 60 side members and a cross connecting member secured to the free end of the rolled awning, the ends of said side members farthest from the awning being provided with a pivotal connection, draft means connected to said 65 cross member for drawing it toward the pivotal connection and causing a telescoping movement of said side members against the action of the spring in the spring actuated rolled awning, and also for causing said side 70 members to swing on their pivots, said draft means and said spring cooperating to keep said awning in taut condition.

6. A structure of the class described comprising a spring actuated rolled awning, a 75 frame therefor comprising freely telescoping side members and a cross connecting member secured to the free end of the rolled awning, the ends of said side members farthest from the awning being provided with a pivotal 80 connection, draft means connected to said cross member for drawing it toward the pivotal connection against the action of the spring in the spring actuated rolled awning, such drawing causing said side members to 85 telescope a predetermined distance and thereafter to swing about said pivotal connection, said draft means and said spring cooperating to keep said awning in taut condition.

7. A structure of the class described, comprising a spring-actuated rolled awning, a frame therefor comprising freely telescoping side members and a cross connecting member secured to the free end of the rolled awning, the ends of said side members farthest from the awning being provided with a permanent 95 pivotal connection, and draft means connected at one end to said cross member for drawing it toward the pivotal connection and causing a telescoping movement of said side members against the action of the spring of said awning and also for causing said side members to swing on their pivots, whereby the cross member is caused to move through an 100 arc, said draft means and said spring co-operating to keep said awning in taut condition, together with means for securing the opposite end of said draft means.

Des Moines, Iowa, February 11, 1926.
